[57] CLAIM

The ornamental design for a dispensing container for pills or the like, as shown and described.

DESCRIPTION

FIG. 1 is a top perspective view of a dispensing container for pills or the like showing my new design; FIG. 2 is a bottom perspective view thereof; FIG. 3 is a side elevational view, the opposite side being the same in appearance;

FIG. 4 is a top perspective view with the cap removed; FIG. 5 is a bottom perspective view with the cap removed;

FIG. 6 is a side elevational view with the cap removed, the opposite side being the same in appearance except that the finish shows a single thread which is a continuation of the thread ends seen in FIG. 6;

FIG. 7 is a top perspective view showing a modified form of my new design with the cap removed;

FIG. 8 is a bottom perspective view thereof;

FIG. 9 is a side elevational view thereof;

FIG. 10 is a top perspective view showing another modified form of my new design with the cap removed;

FIG. 11 is a bottom perspective view thereof; and

FIG. 12 is a side elevational view thereof.

The embodiments of FIGS. 7-9 and 10-12 are identical to the design of FIGS. 1-6 in all respects except for the reduced heights seen best in FIGS. 9 and 12.
